UNITED STATES PATENT OFFICE.

EDWIN G. OGDEN, OF CHICAGO, ILLINOIS.

BARREL-WASHER.

SPECIFICATION forming part of Letters Patent No. 392,220, dated November 6, 1888.

Application filed August 2, 1886. Serial No. 209,811. (No model.)

To all whom it may concern:

Be it known that I, EDWIN G. OGDEN, of Chicago, in the State of Illinois, have invented certain new and useful Improvements in Barrel-Washing Machines, of which the following is a specification.

The invention relates to improvements in barrel-washing machines in which the barrel to be washed is supported and agitated while water is introduced into the same through a pipe entering at the bung-hole; and the objects of my improvements are to simplify the construction of such machines and provide means therein for preventing the waste of water and for aiding in conducting off the wash without splashing it about in the room or place where the machine is used. I attain these objects by the mechanism illustrated in the accompanying drawings, in which—

20 Figure 1 is a front or side elevation of such a machine, showing also a barrel in position to be washed. Fig. 2 is a central vertical section taken on line $x-x$ of Fig. 1. Fig. 3 is an edge view of a detail, being a cushion and plate for holding it in place. Fig. 4 is a plan view of the same. Fig. 5 is a plan or top view of a portion below the line $x-x$ of Fig. 2. Fig. 6 is a side view of the barrel-holding arms and a portion of a screw-rod connected therewith. Fig. 7 is a plan view of the same.

25 The machine comprises a head-piece, as A, provided with legs A'. The head-piece is hollow, and in it is journaled a hollow shaft, B. This shaft is placed vertically in the machine, so that it may serve as a conduit to carry off the wash from the interior of the barrel. To its top end there is attached a cross piece or plate, b, and to this are secured two screw-rods, c, which are provided with barrel-holding arms C, made adjustable by means of nuts on the rods, so that the arms may be set to fit different-sized barrels. The position of the barrel-holding arms with reference to the shaft should always be such as to rest the bilge on the plate or end of the shaft and bring the bung-hole directly over the hollow of the shaft.

30 To the lower end of the shaft a gear-wheel, b', is attached and made to engage with a wheel, d, attached loosely upon an operating-shaft, D, which is provided with a sliding clutch, e, which turns with said operating-shaft,

and may be moved along thereon into and out of engagement with the wheel d, for rotating or stopping the shaft B, and through it the barrel-holding arms. The required shifting of the 55 clutch to thus start or stop the machine without stopping the operating-shaft is effected by means of a forked lever, E, connected with the clutch and pivoted to a cross-brace of the legs at e', so that reverse movements of the long end 60 will slide the clutch on the operating-shaft, so as to bring it into and out of engagement with wheel d.

The water-pipe F, connected with the supply, is extended through the hollow of shaft B, so 65 as to project inside the barrel, and is provided with perforations f at the top, through which the water is discharged into the barrel. The hollow of the shaft B is about the size of the bung-hole, and the size of said water-pipe with 70 reference to the size of said hollow is such as to afford throughout the entire length of said shaft a sufficient passage not occupied by the water-pipe to allow the water to pass out of the barrel at the bung and be conducted off 75 through said passage as fast as it passes in through said pipe.

The water-pipe is provided with a stop-valve at F', the handle or stem of which is connected by a link, a, to the lever E, so that the 80 movements of the lever which respectively connect and disconnect the clutch of the operating-shaft with wheel d for starting and stopping the machine shall also respectively turn on and shut off the water.

85 The exterior of the barrel, resting on the plate or end of the hollow shaft, will ordinarily fit sufficiently close to prevent the escape of any wash outside of the hollow or exit passage through the shaft; but I prefer to use a cushion, 90 a', of rubber or other yielding substance, which will so adapt itself to the surface of the staves under the weight of the barrel as to make a tight joint, which will prevent the escape of wash in all cases; and to keep the cushion in 95 place around the opening it is surrounded and partially covered by a plate, a'', adapted to fit between the rods c and hold the cushion in place with its inner edge projecting above the plate to receive the barrel.

100 In setting up the machine I contemplate arranging the mouth of a conduit directly under

the opening of the hollow shaft to receive and carry off the wash therefrom.

The water-pipe is stationary and supported independently of the hollow shaft, and when a barrel is put on the machine, so as to rest between the arms with the pipe in the bung-hole and the outer adjacent surface resting on the end of the shaft, the forked end of the lever is thrown toward the wheel *d*, so as to cause the 5 clutch to engage therewith and to open the valve of the water-pipe. This starts the barrel to turning and sets the water to running into it in all directions through the openings *f*. The water is thus thrown in contact with the 10 interior of the barrel while in motion, and flows down and out at the bung-hole, and is received into and conducted off through the passage afforded by the hollow of the shaft. The machine is allowed to thus run for a short time 15 until the barrel is cleansed by being thoroughly rinsed, when the lever is reversed, the machine being thereby stopped and the water simultaneously shut off. The motion should not be so rapid as to retain the water in the 20 barrel by centrifugal action, the intention being to have the water run out and off about as fast as it runs into the barrel.

Several of the machines set in a row and having a shaft, *D*, extended under them all may 25 be conveniently tended by one man or boy.

What I claim, and desire to secure by Letters Patent, is—

1. In a barrel-washing machine, the combination, with a vertical shaft provided with a 30 hollow or opening extending longitudinally through it and adapted to cover the bung-hole 35

of a barrel rested on the upper end of said shaft, of an induction water-pipe extended through said hollow for introducing water into the barrel, said hollow throughout being of greater diameter than said pipe, whereby a 40 return-passage for the waste water from the barrel is provided throughout said shaft.

2. In a barrel-washing machine, the combination, with a hollow rotary shaft connected 45 through a top piece with adjustable barrel-holding arms, of mechanism, substantially as described, connected with the lower end of said shaft for operating the same, an induction water-pipe extended through the hollow of said shaft, the diameter of said hollow throughout being larger than said pipe, whereby a return-passage for the wash from the interior of the 50 barrel is provided, substantially as specified.

3. The combination of the vertical rotary 55 hollow shaft, the valved induction-pipe extending through the hollow of said shaft and being of less diameter than said hollow shaft, whereby a return-passage is provided for the waste water, mechanism, substantially as described, for rotating the vertical shaft, a clutch for engaging and disengaging said mechanism, and a link connecting the handle of the valve to the clutch-lever, whereby the movement of 60 said lever to engage and disengage the actuating mechanism opens and closes the valve of the induction-pipe.

EDWIN G. OGDEN.
